UNITED STATES PATENT OFFICE.

JEROME C. BOYLAN, OF CLEVELAND, OHIO.

DOOR-OPERATING DEVICE FOR STOVES AND THE LIKE.

Application filed July 1, 1926. Serial No. 118,797.

REISSUED

My invention relates to an improvement in door operating devices and more particularly to the type of operating devices employed in connection with stove oven doors 5 on the ordinary type of ranges.

An object of my invention is to provide a door operating device which when properly installed will not be seen when the oven door is in either open or closed position. It 10 is a further object of my invention to construct this operating device in such a manner that it will serve partially as a bearing means for the pivoted door so as to thereby eliminate the use of the ordinary heavy 15 hinges usually secured to the outside of the stove frame and which is more or less unsightly.

Another object of the invention is directed to a means for preventing the door 20 from accidentally dropping open and a still further object is the provision of a means for checking the opening movement of the door beyond a predetermined point.

A still further object of my invention is 25 to provide a door operating device which will be neat, small and inexpensive but at the same time very efficient and a device which will be so located that the interior oven space will not be reduced.

30 As a further object of the device there is provided means for automatically closing the oven door and for maintaining it in its closed position until manually opened.

With the objects above indicated and 35 other objects hereinafter explained in view my invention consists in the construction and combination of elements hereinafter described and claimed.

Referring to the drawings:

40 Fig. 1 shows a perspective view of a portion of the frame of the stove and the oven door attached thereto with my hinge properly positioned;

45 Fig. 2 is a rear view of the same showing the manner in which the hinges are secured to the supporting frame;

Fig. 3 is a top plan view with the oven door shown in open position and having the hinge portion in section; and

50 Fig. 4 is a segmentary sectional view through the hinge member showing the arrangement of the spring and the end of the pivoted arm.

55 In the drawings, 10 indicates the frame around the door opening of the lower door of a stove, not shown. This frame is pro-

vided with an upper and lower flange 11 and side flanges 12 which extend into the door opening and are of sufficient width to engage a portion of the door to thereby provide a tight joint and thus prevent the heat from escaping from within the oven.

At the lower portion of the frame 10 and upon the inner surface a recess 13 is provided which serves as a portion of a bearing 65 adapted to receive the extension 14 formed upon the sides and at the lower ends of the door 15.

The door 15 is provided with flanges 15^a and 15^b which engage with the flanges 11 and 12 of the frame 10 when the door 15 is in closed position. An offset 16 is formed in the lower portion of the flanges 15^a and this offset extends inwardly. The upper surface of the offset 16 is provided with a 70 semi-circular portion 16^a and through this portion extends an opening 17.

A block or casting 20 is located within the slot 15^c of the door 15 and is secured thereto by means of bolt 21. This block or 80 casting 20 is provided with a recess 20^c which registers with the recess 13 in the frame 10 and they both thereby form a bearing for the extension 14 on the door 15.

The block or casting 20 is further provided with a portion 20^d which fits within a recess 19 formed in the flanges 12. In fact the entire lower portion of the flange 12 is cut away to accommodate this block or casting 20. The portion 20^d of the casting 20 is cut off at right angles to the vertical portions to form a flat surface 23 which acts as an abutment for the door 15 when in open position as indicated at 36. A recessed portion 20^e is provided in face of the 95 block or casting 20 and is located so as to register with the portion 16^a on the door 15. Adjacent to this recessed portion 20^e is a slot 20^f which extends entirely through the block 20 the purpose for which will be 100 hereinafter explained.

A housing 24 is secured to the block or casting 20 by means of bolts 26 which extend through openings provided in the integral flanges 25. The opening 27 extends 105 entirely through the housing 24 and a slot 28 is provided which extends throughout the entire length thereof and communicates with the opening 27. A rod 32 is screw-threaded into the casting 20 and extends 110 centrally through the opening 27 on the housing 24.

An arm 29 has formed at one end a rounded head portion 29^a which has a central opening 29^b and a pin 30 extends through this opening 29^a and the opening 17 in the offset portion 16. The head portion 29^a is adapted to fit within the recess 16 so that the outer surface thereof is in the same plane as the outer surface of the flange 15^a. The arm 29 is bent inwardly at right angles 10 as indicated at 29^c and is provided with a circular member 31.

The portion 29^a is adapted to slide within the slot 28 and the circular member 31 is adapted to slide within the opening 27 of 15 the housing 24. The arm 29 also extends through the slot 20^c. This circular member 31 has a central opening 34 which receives the rod 32 and permits the same to slide therein.

20 A spring 35 is interposed between the circular member 31 and the casting 20 and is caused to contract when the door is opened.

The oven walls which are not shown are adapted to be applied in the usual manner 25 and when so applied completely cover up the device and prevent the heat from coming in contact with it. This is due to the fact that the device is always within an air pocket between the walls of the stove and 30 the walls of the oven.

In operating the device as the door 15 is opened the arm 29 being attached thereto and having the circular portion 31 formed thereon is caused to engage the spring 35 thereby contracting the same. This spring 35 prevents the door 15 from banging open or accidentally flying open and as the door reaches its substantially horizontal position the bottom corner of the door 15 engages or 40 abuts the surface 23 formed on the member 20 as indicated at 36 and prevents further open movement thereof.

When it is desired to close the door it is raised slightly from the horizontal and the 45 springs 35 are of sufficient tension to draw the door into closed position.

While I have described the preferred embodiment of my invention it is to be understood that I am not to be limited to the specific construction contained herein but many changes may be made without departing from the spirit of the invention as contained 50 in the appended claims.

Having thus described my invention, I 55 claim:

1. In a door operating device for stoves and the like, the combination of a frame provided with an opening therein, a door pivoted to said frame and adapted to close said 60 opening, a member secured to said frame upon the side opposite to said door and provided with a central opening, a spring in said latter opening, and an arm extending through said door opening having one end 65 secured to said door and having the opposite

end within said member opening and engaging said spring.

2. In a door operating device for stoves and the like, the combination of a frame 70 provided with an opening therein, a door pivoted to said frame and adapted to close said opening, a member secured to said frame and provided with a central opening, said member being further provided with a slot communicating with said opening, resilient means within said opening, and an arm having one end pivotally attached to said door and having its opposite end engaging said resilient means, said arm being adapted to travel within said slot upon the 75 door being opened or closed.

3. A door operating device for stoves and the like, comprising a member adapted to be rigidly secured to the frame of a stove and having a central opening therein, resilient 80 means within said opening, and an arm having one end engaging said resilient means and the opposite end adapted to be secured to a door.

4. A door operating device for stoves and the like, comprising a member adapted to be rigidly secured to the frame of a stove and having a central opening therein, a spring within said opening, a rod screw-threaded into said member and extending 90 centrally of said spring, and an arm having one end slidably engaging said rod and adapted to act against the tension of said spring, and the opposite end provided with means adapted to be pivotally secured to a 95 door.

5. A door operating device for stoves and the like, comprising a member adapted to be secured to the frame of a stove and provided with a central opening, said member being further provided with a slot communicating with said central opening, a spring within said opening, a rod extending centrally of said opening and said spring, and an arm having one end bent at substantially right 105 angles to extend through said slot and formed with a head of substantially the same diameter as the opening in said member, said head being provided with an opening adapted to slidably engage said rod and the end of said spring, and the opposite end adapted to engage a door.

6. In a door operating device for stoves and the like, the combination of a frame provided with an opening therein, a door pivoted to said frame and adapted to close said opening, members secured to the inner portion of the frame adjacent said door, resilient means in said members, and arms having one end engaging said resilient means and the opposite end extending through said opening and pivotally attached to the sides 125 of said door.

7. In a door operating device for stoves and the like, the combination of a frame pro- 130

- vided with an opening therein, a flange extending into and entirely surrounding said opening, the lower portion of the side flanges being cut away, a member secured to the frame and having a portion extending into said cut portion, said member being further provided with a tubular extension, a slot in the tubular extension extending longitudinally thereof, a spring within said tubular extension, and an arm having a portion extending through said slot into engagement with the end of the spring and having its opposite end extending through an opening in said member into pivotal engagement with said door. 55
8. In a door operating device for stoves and the like, the combination of a frame having outer walls and oven walls formed with a space between said frame being provided with an opening therein, a door pivotally attached to said frame and adapted to close said opening, a member having a tubular extension, said member being attached to said frame and extending between the outer wall and the oven wall, resilient means in said tubular extension, and an arm having one end engaging the resilient means and the opposite end extending through the opening and pivotally engaging said door. 70
9. In a stop or check for stove doors and the like, a frame provided with an opening surrounded by a flange, the lower portion of which is cut away to provide an opening, a member secured to the frame and having a portion extending into the opening, the lower end of said member being cut away to form a horizontal stop, and a door pivoted to said frame, the inner end of said door abutting said stop when in open position. 80
10. In a door operating device for stoves and the like, the combination of a frame provided with an opening therein, a door pivoted at the lower portion of the frame and adapted to close said opening, a member secured to the inner side of said frame, said member forming with said frame a bearing for said door, said member being further provided with a horizontally disposed tubular extension, a spring disposed within said tubular member, and an arm having one end in engagement with said spring, the opposite end extending forwardly through said opening into pivotal engagement with said door. 85
11. In a door operating device for stoves and the like, the combination of a frame provided with an opening, a door pivotally attached to the lower portion of said frame and adapted to close said opening, a member secured to the inner surface of the frame adapted to cooperate with said frame to form a bearing for said door, said member being provided with a horizontal abutment adapted to be engaged by said door when in open position, a horizontally disposed tubular extension carried by said member and extending inwardly therefrom, a spring within said tubular member, and an arm having one end engaging said spring while the opposite end extends outwardly through an opening provided in said member into pivotal engagement with said door. 90
12. In a stop or check for stove doors and the like, a frame provided with an opening the lower portion of which is cut away to provide a recess, a door pivoted at the lower portion of the frame and adapted to close said opening, and a member positioned in said recess and secured to the inner side of said frame and cooperating with the latter to form a bearing for said door, said member being cut away to provide a horizontal stop adapted to be engaged by the door when in opened position. 95
13. In a door operating device for stoves and the like, the combination of a frame provided with an opening therein, a door pivoted to said frame and adapted to close said opening, a member secured to the inner side of said frame and having portions cooperating with said frame to form a bearing for said door, an arm pivotally connected to said door and extending through a slot in said member, and resilient means carried by said member with which the free end of said arm engages. 90
- In testimony whereof, I hereunto affix my signature:
- JEROME C. BOYLAN.
